(Cl. D87—5)

Fig. 2

Fig. 1

Fig. 4

Fig. 3

FIGURE 1 is a top plan view of a mailing or carrying case for phonograph records or the like showing our new design, in closed condition;

The broken line showing of an identification label in FIG. 1 is for illustrative purposes only. The fragmentary stippling is representative of the appearance of the entire side of FIG. 1.

We claim:

The ornamental design for a mailing or carrying case for phonograph records or the like, as shown and described.
